UNITED STATES PATENT OFFICE.

DELBERT F. AXELSON, OF LOS ANGELES, CALIFORNIA, ASSIGNOR TO AXELSON MACHINE CO., A COPARTNERSHIP COMPRISING C. F. AXELSON AND G. A. AXELSON.

PUMP-CYLINDER.

1,271,260.

Specification of Letters Patent.

Patented July 2, 1918.

Application filed December 5, 1916. Serial No. 135,262.

To all whom it may concern:

Be it known that I, DELBERT F. AXELSON, a citizen of the United States, residing at Los Angeles, in the county of Los Angeles and State of California, have invented a new and useful Pump-Cylinder, of which the following is a specification.

My invention relates to oil well apparatus, and particularly to the pumps which are 10 placed in the bottom of an oil well and which are actuated through a suitable string of pump rods for the purpose of raising the oil to the surface of the ground.

The principal object of my invention is 15 to produce certain improvements and refinements in such pumps, and to provide a novel method of producing same.

More particularly, my invention relates to the liners which are used in such pumps, 20 and a further object of the invention is to produce a novel form of liner which can be produced in quantities and which will be absolutely interchangeable.

Further objects and advantages will be 25 referred to and described more particularly hereinafter.

Referring to the drawings, which are for illustrative purposes only:

Figure 1 is an application figure, being 30 an elevation of a portion of an oil well with a pump embodying my invention installed therein.

Fig. 2 is a vertical cross section on an enlarged scale of a portion of the apparatus 35 illustrated in Fig. 1.

Fig. 3 is a section on a plane represented by the line 3—3, Fig. 2.

In the embodiment of my invention shown in the drawings, an oil well 11 is shown 40 which terminates at the surface of the ground 12, upon which is placed a derrick 13 containing any standard form of pumping apparatus. The well 11 may be lined with casing 14, and the oil may be raised 45 through tubing 15. Threaded on the lower end of the tubing 15 is an upper collar 16. This collar is provided with a central opening 17 which is connected by means of a finished shoulder 18 with a liner seat 19.

50 The liner seat 19 connects through a shoulder 20 and a fillet 21 with a threaded opening 22 in which a shell 23 is secured. The lower end of the shell 23 is secured in a lower collar 24 which is exactly similar

in construction to the collar 16, being how- 55 ever reversed. Liners 30 are placed inside the shell 23, these liners having a central bore 31 and a series of rings 32 turned on the outer surface thereof. The interior of the shell 23 is accurately reamed to the same 60 diameter as the seat 19, this diameter being practically the same as the external diameter of the liners 30. The liners 30 abut against each other and are solidly clamped between the seats 19 when the collars 24 and 16 are 65 screwed together on the shell 23.

In the practical production of my invention, I first accurately ream the shell 23 and the seats 19 to a predetermined diameter. I then grind the liners 30 to a smaller predetermined diameter, this diameter being suitable for the reception of a plunger 40 which is actuated through a suitable string of pump rods 41. The liner 30 is then placed on a mandrel and the exterior of the rings 75 32 is accurately ground so that they will slide inside the shell 23 and fit in the seats 19.

By the use of my invention the liners 30 may be made in quantities of a definite 80 standard dimension, and they may be readily replaced as the bore wears. As the inside and outside diameters of the liners 30 are made absolutely concentric by my method of manufacture, substitutions there- 85 of may be made at any time by an ignorant or unskilled person with the assurance that they will operate properly. The liners 30 are rounded off, as shown at 51, so that sharp cutting edges will not be left to cut into the plungers as they are inserted or 90 withdrawn.

I claim as my invention:

1. In an oil well pump, a shell; an upper collar into which said shell is threaded; a lower collar into which said shell is threaded; and a series of liners, each liner fitting accurately inside said shell and having a central opening truly concentric with its outside diameter, said liners being seated at either end in said collars and being tightly 95 clamped together between said collars. 100

2. A combination as in claim 1 in which the periphery of the liner consists of a series of accurately ground rings.

In testimony whereof, I have hereunto 105 set my hand at Los Angeles, California, this 20th day of November, 1916.

DELBERT F. AXELSON.
